UNITED STATES PATENT OFFICE.

EDWARD J. SCHNEIDER, OF ST. LOUIS, MISSOURI.

WHISTLE.

1,382,744.

Specification of Letters Patent. Patented June 28, 1921.

Application filed March 18, 1921. Serial No. 453,431.

To all whom it may concern:

Be it known that I, EDWARD J. SCHNEIDER, a citizen of the United States, residing at the city of St. Louis, Missouri, have invented a new and useful Whistle, of which the following is a specification.

This invention relates to whistles, of the type used for signaling purposes in connection with vehicles and engines.

10 An object of the invention is to provide a whistle of an improved and efficient construction that may be economically manufactured, which is composed of a minimum number of parts united in a novel and efficient manner.

The drawing is a sectional view of my improved whistle.

In the embodiment shown in the drawing, the whistle includes a stem having a 20 threaded portion 1 for connection with the part to which the whistle is to be attached. The stem is formed with a circumferential shoulder or flange 2, serving as a support for a bowl or chamber 3. A passage 4 is 25 formed within a stem extending from the lower end of the stem to a joint within the bowl 3 and ports 5 opening from the upper end of the passage 4 into the bowl 3.

The dome 6 of the whistle is of proper 30 dimensions and has its lower edge bent to provide an oblique flange 7 bearing against the inner surface of the flaring portion of the wall of the bowl 3.

An upper wall is provided for the bowl 35 or chamber 3, comprising a wall member 8, having a beveled edge pressing against the flange 7 throughout the circumference of said wall member 8, and forming, practically, an air-tight joint. The stem extends 40 through the wall member 8 and has threads on its upper end receiving the nut 9, which is screwed to position to clamp the parts together, as shown.

The inner side of the wall of the dome 45 6 is cut out or removed to form the opening 10.

The valve controlling the admission of the air or steam into the whistle comprises a valve member 11, arranged to seat against 50 the lower end of the stem, containing the passage 4 in order to close said passage. The flange stem 12 in connection with the valve 11, extends axially through the passage 4, and through the upper portion of 55 the stem containing said passage, into the dome 6. The protruding end of the stem

12 is encircled by a spring 13 of the expansion type, having its lower end bearing against the end of the stem in which the valve stem is mounted, and its upper end bearing against an abutment 14 in connection with the valve stem 12. Arranged in this manner, this spring 13 is operated to hold the valve 11 in closed position and will yield under pressure to permit the valve 11 to be moved to open position.

For moving the valve to open position, in opposition to the power of the spring 13, I provide a lever 15, pivoted to a support 16, and having its inner end adjacent to the upper end of the valve stem 12, so that by proper manipulation of the lever, the valve may be opened. After the lever 15 is released, the valve will be closed automatically by the spring 13.

The air or steam jet opening 17 is formed through the wall member 8, adjacent to the opening 10 through the dome 6, so that when the air or steam is forced through said opening 17 the whistling sound results.

I claim:

1. A whistle of the character described comprising, a supporting stem, an abutment on said stem, a chamber on said stem bearing against said abutment, a dome having 85 its edge within said chamber, a wall member clamping the edge of said dome against the wall of the chamber, a valve supported in said stem, a spring for holding the valve closed and a lever for opening the valve in opposition to said spring.

2. A whistle of the character described comprising, a supporting stem, an abutment on said stem, a chamber on said stem bearing against said abutment, a dome having its edge within said chamber, a wall member pressing the edge of the dome against the wall of the chamber, an element on said stem holding said wall member in position, a passage through said stem opening into said 100 chamber, a passage through said wall member into the dome, a valve supported by said stem for closing the passage in said stem, a spring holding said valve closed, and a lever supported by said wall member for opening 105 said valve in opposition to said stem.

3. A whistle of the character described comprising, a supporting stem, a flange on said stem, a chamber on said stem supported by said flange, and having the upper portion of the wall thereof flaring outwardly, a dome having an opening through the inner

side thereof, an oblique flange on said dome, extending into the flaring portion of said chamber, a wall member pressing said dome flange against the flaring portion of said chamber, an element on said stem holding said wall member in clamping position, a passage through said stem into said chamber, a valve supported by said stem for open-

ing and closing said passage, a spring holding said valve closed, a lever supported by said wall member for opening said valve, and a passage through said wall member opening into said dome, near the opening through the wall of the dome. 10

EDWARD J. SCHNEIDER.
